CLAIM

The ornamental design for a wireless charger, as shown and described.

DESCRIPTION

FIG. 1 is a front, bottom perspective view of a first embodiment of a wireless charger, showing my new design; FIG. 2 is a rear, top perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of detail "9" identified in FIG. 1; FIG. 10 is an enlarged view of detail "10" identified in FIG. 2; FIG. 11 is a perspective view of the first embodiment of the wireless charger, shown in an alternative configuration; FIG. 12 is a front, bottom perspective view of a second embodiment of the wireless charger; FIG. 13 is a rear, top perspective view thereof; FIG. 14 is a front elevation view thereof; FIG. 15 is a rear elevation view thereof; FIG. 16 is a left side elevation view thereof; FIG. 17 is a right side elevation view thereof; FIG. 18 is a top plan view thereof; FIG. 19 is a bottom plan view thereof; FIG. 20 is an enlarged view of detail "20" identified in FIG. 12; FIG. 21 is an enlarged view of detail "21" identified in FIG. 13; and, FIG. 22 is a perspective view of the second embodiment of the wireless charger, shown in an alternative configuration. The broken lines in the figures depict portions of the wireless charger that form no part of the claimed design.
